WILLIAM M. STEWART, OF MILWAUKEE, WISCONSIN.

GAS-ENGINE.

1,117,319.

Specification of Letters Patent. Patented Nov. 17, 1914.

Application filed March 23, 1912. Serial No. 682,770.

To all whom it may concern:

Be it known that I, WILLIAM E. BROWN, a citizen of the United States, and resident of Milwaukee, in the county of Milwaukee, and State of Wisconsin, have invented new and useful Improvements in Gas-Engines, of which the following is a description, reference being had to the accompanying drawings, which are a part of this specification.

This invention relates to gas engines of the two cycle type and has for its object to dispense with the use of valve mechanism other than the piston itself and its cooperating ports in the walls of the cylinder.

Another object of the invention is to dispense with the compression of the charge in the crank case as with ordinary two cycle engines and to introduce the charge under compression into one end of the combustion chamber while exhausting the burnt gases at the opposite end of the combustion chamber.

With the above and other objects in view the invention consists in the gas engine as herein claimed and all equivalents.

In the accompanying drawing the view is a sectional elevation of a two cycle engine constructed in accordance with this invention though the invention is not confined to an engine of two cylinders.

In these drawings 10 indicates the engine casing in which the usual crank shaft 11 is provided with the flywheel 12 and the connecting rods 13, but without cams. The connecting rods 13 connect with pistons 14 which slidably fit in cylinders 15. The pistons and the cylinder, however, are not of the ordinary type, for each piston has a cylindrical extension 16 forming its upper portion of the same diameter as its lower portion and terminating in an outwardly extending flange forming a trunk piston 17 within a cylinder extension 18 on top of the cylinder 16. The cover or cylinder head 19 for the extension 18 of each cylinder has a downwardly extending hollow plunger 20 fitting within the interior of the piston extension 16 forming a stationary plunger within a movable cylinder. The space within the piston extension 16 and between the stationary plunger 20 and the piston proper 14 constitutes a combustion chamber 21 and a spark plug 22 passing through the stationary plunger 20 serves to ignite the

charge of explosive gas within this combustion chamber.

In the drawing the piston at the left is at its extreme upper position while the piston at the right is at its extreme lower position. The piston members have recesses 23 around their intermediate portions which in the uppermost position of the piston register with a series of intake ports 24 in the walls of the cylinder and with the interior of the cylinder extension 18 below the trunk piston 17 which space will be referred to as the compression chamber 25. As the result of this connection the partial vacuum produced in the compression chamber 25 by the upward movement of the trunk piston 17 causes a charge of explosive mixture to be drawn into the compression chamber 25 from an intake passageway 26 surrounding the cylinders and connected with a carburetor not shown. This charge is compressed in the compression chamber 25 during the downward movement of the piston and until a series of ports 27 in the piston extension 16 pass below the plunger head 20 as at the right of the drawing when the compressed charge in the compression chamber 25 enters the combustion chamber 21 through said ports 27. This forcible admission of the fresh charge at the upper end of the combustion chamber through numerous ports 27 effectively scavenges the combustion chamber driving the burnt gases downwardly and out through ports 28 at the bottom of the combustion chamber which at this time register with exhaust ports 29 at the lower end of the cylinder which communicates with an exhaust passageway 30 surrounding the cylinders and have an exhaust pipe connection not shown.

In order that the trunk pistons 17 may not be retarded in their movements by a confined space above them openings 31 are provided in the walls of the plunger 20 near the upper end thereof and in order to utilize the air current passing through these openings for cooling the cylinder a frusto conical deflector 32 extends from the cylinder head 19 down into the space within the stationary plunger 20 to near the lower end thereof, thus causing the air current to travel close to the heated plunger head forming one wall of the combustion chamber. In addition to this the air traveling

on opposite sides of the upper walls of the plunger 20 serves to keep them cool and as the walls of the piston extension 16 travel in contact therewith the air serves to assist 5 in cooling them.

In operation the engine acts as a two cycle engine the charge under compression being admitted to the upper end of the combustion chamber, however, and driving the burnt 10 gases out of the lower end of the combustion chamber, thus assuring a more complete exchange of fresh explosive mixture for burnt gases without their commingling to impair the effectiveness of the following explosion. 15 Furthermore these results are accomplished without the use of valves other than those formed by the openings in the piston registering with openings in the cylinder. If it is found difficult to start the engine by rea- 20 son of the suction produced by one trunk piston 17 before the compression chamber in which it is contained communicates with the intake ports and by reason of the compression produced by the other trunk piston 25 17 before the compression chamber in which it is located communicates with the combustion chamber pet cocks 33, preferably in the form of ordinary priming valves, may be provided in the walls of the cylinder extension 30 18 approximately midway the length of the stroke of the trunk piston 17 and these valves may be left open to relieve such suction and compression during part of the stroke of the piston and thus facilitate the 35 starting of the engine when the valves may be closed. By removing the cylinder heads 19 the plungers 20 are withdrawn and the entire interior of the engine becomes accessible for cleaning or repairing while the 40 spark plugs 22 are accessible at all times through the openings of the cylinder heads.

What I claim as new and desire to secure by Letters Patent is:

1. A two cycle engine, comprising a cylinder, a cylindrical piston operating therein, a stationary plunger fitting within the cylindrical piston and forming a combustion chamber in the interior thereof, an extension on the cylinder of larger diameter, a flange 45 on the piston forming a trunk piston in the extension of the cylinder and constituting with the cylinder extension a compression

chamber, there being ports in the piston clearing the plunger at the end of the explosion stroke of the piston for establishing 55 communication between the compression chamber and the combustion chamber, there being ports in the piston at the other end of the combustion chamber uncovered at the end of the explosion stroke of the piston 60 through which the exhaust gases may be forced by the incoming compressed charge from the compression chamber, and an intake port on the cylinder, there being a recess in the piston connecting the intake port 65 with the compression chamber at the end of the compression stroke of the piston.

2. A two cycle gas engine, comprising a cylinder, a cylindrical piston working therein, an extension on the cylinder of larger 70 diameter, a flange on the piston forming a trunk piston working within the extension cylinder to form a compression chamber, a cylinder head on the cylinder extension having a central opening, a plunger projecting 75 from the cylinder head and working within the cylindrical piston and forming a combustion chamber in the interior thereof, there being ports in the piston clearing the plunger at the end of the explosion stroke 80 of the piston connecting the compression chamber with the combustion chamber, an exhaust passageway in the cylinder, there being a port in the piston communicating with the exhaust passageway at the end of 85 the explosion stroke of the piston, an intake passageway in the cylinder, there being a recess in the piston connecting the intake passageway with the compression chamber at the end of the compression stroke of the 90 piston, said plunger being provided with openings above the trunk piston, a spark plug in the plunger, and a tubular deflector projecting from the cylinder head to near the end of the plunger to cause the air forced 95 through said openings to travel close to the walls of the plunger.

In testimony whereof, I affix my signature, in presence of two witnesses.

WILLIAM E. BROWN.
